COAT RACK

Violet R. Rodin, 61-69 82nd St.,
Middle Village, N.Y. 11379

Filed Apr. 6, 1967, Ser. No. 6,557

Term of patent 14 years

(Cl. D33—8)

I claim:

The ornamental design for a coat rack, as shown.
